UNITED STATES PATENT OFFICE

169,570

PAIR OF SUNGLASSES

Egon F. Von Seekamm, New York, N. Y., assignor
to Wilson Products, Inc., Reading, Pa., a cor-
poration of Pennsylvania

Application August 6, 1952, Serial No. 20,915

Term of patent 14 years

(Cl. D57—1)

To all whom it may concern:

Be it known that I, Egon F. Von Seekamm, a citizen of the United States of America, residing in New York city, county of New York, and State of New York, have invented a new, original, and ornamental Design for a pair of Sunglasses, of which the following is a specification, reference being had to the accompanying drawing, forming part thereof, wherein:

Figure 1 is a front perspective view of a pair of sunglasses embodying my new design.

Figure 2 is a top plan view thereof, wherein the temples are shown broken away.

Figure 3 is a side perspective view thereof.

I claim:

The ornamental design for a pair of sunglasses, substantially as shown.

E. F. VON SEEKAMM.
